[57] **CLAIM**

The ornamental design for a combined specimen tube and paperwork pouch, as shown and described.

DESCRIPTION

FIG. 1 is a front elevation of a combined specimen tube and paperwork pouch in a fully assembled condition; FIG. 2 is a rear elevational view; FIG. 3 is a side elevational view; FIG. 4 is a bottom plan view; and FIG. 5 is a front elevational view with the closure flap in the open position.

The broken lines representing the specimen tube in FIG. 5 are shown for illustrative purposes only.

FIG-1

FIG-2

FIG-3

FIG-4
